W. J. STILL

TWO-STROKE INTERNAL COMBUSTION ENGINE

Filed Sept. 1, 1921

Inventor
William Joseph Still
By B. Anger, Atty

UNITED STATES PATENT OFFICE.

WILLIAM JOSEPH STILL, OF LONDON, ENGLAND.

TWO-STROKE INTERNAL-COMBUSTION ENGINE.

Application filed September 1, 1921. Serial No. 497,700.

To all whom it may concern:

Be it known that I, WILLIAM JOSEPH STILL, a subject of the King of Great Britain, and resident of London, England, have invented certain new and useful Improvements in and Relating to Two-Stroke Internal-Combustion Engines, of which the following is a specification.

This invention relates to two stroke internal combustion engines of that character wherein inlet and exhaust ports are uncovered by the engine piston. In such engines as hitherto constructed the exhaust port has necessarily been so designed and located relative to the inlet port that it is uncovered by the engine piston slightly before the inlet port is uncovered to admit the scavenging air charge and of course closes after the inlet port has closed. It follows as a consequence that after the inlet port has closed there is an escape of some portion of the charge within the cylinder the charge escaping until the exhaust port has also closed.

The effect of this is to reduce the weight of the charge within the cylinder. It has been suggested to counteract this by raising the pressure of the scavenge air and another method which has been suggested is to provide a throttling valve in the exhaust pipe of the engine. The present invention also has for its object to provide a two stroke internal combustion engine in which the weight of the air charge retained within the cylinder is increased beyond that possible with the usual construction, and consists broadly of a two stroke internal combustion engine having an auxiliary exhaust or pressure release port adapted to be opened prior to the opening of the main exhaust port. A further feature of the invention consists in so arranging the scavenging charge inlet port that it will be uncovered by the engine piston prior to the uncovering of the exhaust, and providing means for lowering the pressure in the cylinder before the end of the expansion stroke.

The invention further comprises a two-stroke internal combustion engine in which the engine piston acts as a valve over the inlet and exhaust ports, wherein communication between the cylinder and the exhaust outlet is cut off prior to cutting off communication between the cylinder and the scavenging charge inlet, and established prior to establishing communication between

the cylinder and the scavenging charge inlet.

In the embodiment of the invention illustrated by the accompanying drawing the charge inlet or scavenging port 1 of the cylinder 3 is so disposed relatively to the exhaust port 2 that the inlet port 1, during the outward stroke of the piston 4, will be uncovered prior to the uncovering of the exhaust port 2, and will be closed by the piston 4 during its return stroke, after the closing of the exhaust port 2.

The cylinder 3 is provided with a release port 5 having a cylindrical portion 6 bored to receive a piston valve 7. This valve is operated from the cam shaft of the engine by a connecting rod 8 connected to a cam or other suitable device on the cam shaft or driven therefrom in any suitable manner.

During the expansion stroke of the engine, the release valve 7 opens and the gases within the cylinder escape by their own pressure when the piston uncovers the release ports in the cylinder wall, and the pressure within the cylinder 3 falls to or below atmospheric pressure. The inlet scavenge port 1 is then uncovered followed immediately after by the uncovering of the exhaust port 2 and scavenging is effected in the usual way. The release valve 7 is closed and the exhaust port 2 is again covered prior to final closure of the inlet port 1 and thus there is a rise of pressure in the scavenge main just before the inlet 1 closes. It follows that the charge within the cylinder 3 will be the full swept volume of the stroke of the piston from the point of closure of the exhaust port 2 at a pressure something above atmospheric pressure. Thus the weight of charge will be increased for two reasons. In the first place it will be increased by the greater swept volume consequent upon the exhaust port 2 being lower than the inlet port 1 and secondly it will be at an increased pressure without involving any increase in the scavenge pump pressure.

The clearance space between the piston valve 4 and the engine cylinder 3 can be very small and moreover the work done in compression into this space will not be wasted since any compressed air in this space will be re-expanded with the movement of the piston valve.

What I claim and desire to secure by Letters-Patent is:

A two stroke internal combustion engine

comprising a cylinder, a series of openings in the wall of said cylinder adapted to constitute a scavenging charge inlet port, a further series of openings in the wall of the cylinder on the opposite side of said inlet port adapted to constitute a main exhaust port, a piston reciprocable in said cylinder and adapted to function as a valve for opening and closing said inlet and exhaust ports, the openings constituting the inlet port being of greater depth than the opening constituting the main exhaust port whereby said inlet openings are uncovered by the piston on its expansion stroke earlier than the main ex-

haust port openings and covered by such piston on its compression stroke later than said exhaust port, and a valve controlled auxiliary exhaust port disposed above the level of the main exhaust port adapted to open on the expansion stroke of the piston so as to lower the pressure in the cylinder before the main exhaust port is uncovered and to close upon the compression stroke of the piston whereby the inlet port remains open for a short period after both exhaust ports are closed. 15
